LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,211,049.

Specification of Letters Patent. Patented Jan. 2, 1917.

Application filed June 9, 1914. Serial No. 343,925.

To all whom it may concern:

Be it known that I, LEWIS C. BAYLES, a citizen of the United States, residing at Easton, in the county of Northampton and State of Pennsylvania, have invented a certain new and useful Improvement in Fluid-Operated Percussive Tools, of which the following is a specification.

This invention relates to fluid operated percussive tools, and more particularly to tools of the type wherein the admission of fluid is controlled primarily by the movement of the piston.

The object of this invention is to provide an auxiliary valve for controlling the admission of fluid to one end of the cylinder to increase the efficiency of the piston blow. This object is accomplished by the invention, a practical embodiment of which is shown in the accompanying drawings, in which,

Figures 1 and 2 are longitudinal sections showing the piston and the auxiliary valve in different positions.

In the drawings is shown a cylinder 1 which consists of a smaller rearward bore 2 and a larger forward bore 3, a piston 4 being provided which has a head 5 sliding in the forward bore 3 and a shank 6 sliding in the rearward bore 2, there being a neck 7 between the head and shank of the piston.

Fluid is admitted constantly to the rear end of the bore 3 by a passage 8. From the forward end of the bore 2, so placed as to be put into communication with the rear end of the bore 3 by the neck 7 near the rear end of the piston stroke, a passage 8^a leads to the rear end of the bore 2. From a port 9 in the rearward part of bore 3 a passage 10 leads to the forward end of the bore 3.

To control the opening of the port 9 a valve 11 is provided which has a head 12 sliding in a valve chest 13 and a separate portion 14 projecting into the bore 10 and adapted in its forward position to close the port 9, the head 12 being provided with opposed operating faces. To the rearward end of the valve chest 13 a passage 15 leads from the rearward end of the bore 2 and to the forward end of the valve chest 13 a passage 16 leads from the bore 3 at such a point that it will be uncovered by the piston head near the end of its stroke in both directions.

From the side of the bore 2 an exhaust passage 17 leads to the atmosphere, it being

so placed that it is uncovered by the rear face of the shank 6 near the end of the piston stroke while from the side of the bore 3 an exhaust passage 18 leads to atmosphere and is so placed as to be uncovered by the forward end of the piston head 5 near the end of the rearward stroke of the piston.

In operation, supposing the parts to be as shown in Fig. 2, fluid is being admitted to the rear end of the bore 3 and to the rear end of the bore 2 through the passage 8^a. With the piston in this position there will be pressure on the rearward face of the valve head 12 and no pressure on its forward surface so that the valve 11 will be in its most forward position, the controlling portion 14 closing the port 9. The pressure on the rearward surfaces of the piston will drive it forward, the fluid in the forward part of the bore 3 exhausting for a portion of the stroke through the port 18.

As the piston moves forwardly the shank 6 will cover the port 8^a, the piston thereafter moving forward under the influence of the constant pressure on the rear face of the piston head and the expansion of the fluid in the bore 2. As the piston moves forward the rear face of the piston head will uncover the port 9, but by reason of the valve 11 no fluid can pass through the port 9 to the forward end of the bore 3. When the piston, however, reaches the position shown in Fig. 1 the opening of the passage 16 will be uncovered allowing fluid to pass into the forward end of the valve chest 13. At the same time the pressure in the rear end of the bore 2 will be exhausted through the opening of port 17 by the forward movement of the shank 6. The valve 11 will, therefore, move rearwardly admitting fluid through the port 9 to the forward end of the bore 3. This will cause the piston to move rearwardly until its movement is checked by the pressure on the rearward surfaces of the piston, the admission of fluid to the forward end being cut off when the piston head covers the port 9.

When the piston nears the end of its rearward stroke, the passage 16 will be opened to atmosphere through the port 18 and live pressure will again be admitted through the passage 8^a to the rear end of the bore 2 and to the rear end of the valve chest 13 through the passage 15 with the result that the valve 11 will move forwardly again closing the port 9.

It is to be understood that while the present showing and description discloses only one specified modification of the invention, other forms and modifications are included 5 in the spirit and scope of the invention, as expressed in the claims.

What I claim is:

1. In a fluid operated percussive tool, a cylinder having a smaller rearward portion 10 and a larger forward portion, a piston having a shank sliding in said rearward cylinder portion and a head sliding in said forward cylinder portion, means for admitting fluid constantly to the rearward end of said larger 15 cylinder portion, a passage controlled by the piston for admitting fluid into the rearward end of the cylinder near the rearward end of the piston stroke, a passage for admitting fluid into the forward end of said 20 cylinder, said passage having a port uncovered by the piston, a valve controlling said port, means for moving said valve to open said port near the end of the forward stroke of the piston, and means for moving said 25 valve to close said port near the end of the rearward stroke of the piston.

2. In a fluid operated percussive tool, a cylinder having a rearward portion of smaller diameter and a forward portion of 30 larger diameter, a piston having a shank sliding in said rearward cylinder portion and a head sliding in said forward cylinder portion, said piston having two small surfaces for driving it forward and a large 35 surface for driving it rearward, a fluid passage for admitting fluid to a portion of the cylinder to exert a constant pressure on one of said smaller surfaces, a passage controlled by the piston for admitting fluid to exert 40 pressure on the other of said smaller surfaces near the end of the piston's rearward stroke, a passage to the forward end of the cylinder and adapted to be put into communication with the constant pressure portion of 45 the cylinder by the movement of said piston, a valve controlling said passage having a port controlling portion, and a separate operating portion having operating surfaces, a passage opened by the piston near the forward end of its forward stroke to convey 50 fluid under pressure from the cylinder to an operating surface of said valve to move it

to open said port, and means to move said valve to close said port near the rearward end of the piston stroke.

55

3. In a fluid operated percussive tool, a cylinder having a smaller rearward portion, and a larger forward portion, a piston having a shank sliding in said rearward cylinder portion and a head sliding in said forward cylinder portion, means for admitting fluid constantly to the rearward end of said larger cylinder portion, a passage controlled by said piston for admitting fluid into the rearward end of the cylinder near the rearward end of the piston stroke, a passage for admitting fluid into the forward end of said cylinder, said passage having a port uncovered by the piston, a valve for controlling said port having a port controlling portion 70 and a separate operating portion having operating surfaces, a passage opened by the piston near the forward end of its forward stroke to convey fluid under pressure from the cylinder to an operating surface of said 75 valve to move it to open said port, and means to move said valve to close said port near the rearward end of the piston stroke.

60

4. In a fluid operated percussive tool, a cylinder having two different diameters, a piston having a head sliding in the larger bore, a shank sliding in the smaller bore of said cylinder, and a neck connecting said head and shank, means for admitting fluid constantly to the end of the larger bore 80 surrounding said neck, a passage controlled by the piston and operating in conjunction with said piston neck for admitting fluid from said end of the larger bore to the outer end of said smaller bore, a passage overrun 85 by said piston head for admitting fluid from said end of the larger bore to the outer end of said larger bore, a valve controlling said port, and means for moving said valve to open said port when the piston reaches the 90 end of its stroke toward the outer end of said larger bore.

65

In testimony whereof, I have hereunto set my hand.

LEWIS C. BAYLES.
